UNITED STATES PATENT OFFICE.

SAMUEL C. FREDSON, OF KENOSHA, WISCONSIN.

TOY.

1,311,337.

Specification of Letters Patent. Patented July 29, 1919.

Application filed November 16, 1917. Serial No. 202,359.

To all whom it may concern:

Be it known that I, SAMUEL C. FREDSON, a citizen of the United States, and a resident of Kenosha, in the county of Kenosha and State of Wisconsin, have invented a new and useful Improvement in Toys, of which the following is a specification.

My invention relates to improvements in toys, and it consists in the constructions, and 10 arrangements herein described and claimed.

An object of my invention is to provide a building toy consisting essentially of a strip or strips of material having slots cut therein at various angles and in various positions, so 15 that the strips may be fitted together in said slots and construct the representation of the framework of a building.

Other objects and advantages will appear in the following specification, reference being had to the accompanying drawings, in 20 which:

Figure 1 is a side elevation of one of the strips showing the slots cut at various angles and located in various positions.

25 Fig. 2 is a detail perspective view showing two of the strips fitted together at right angles to each other.

Fig. 3 is an enlarged detail view showing how the strips may be fitted together at 30 angles with respect to each other.

Fig. 4 is a detail perspective view showing another method of fitting the strips together.

Fig. 5 is a detail plan view showing a slightly modified arrangement.

35 Fig. 6 is a detail perspective view showing how the form illustrated in Fig. 5 may be bent into the shape of a channel.

Fig. 7 is a detail view of one of the keys.

Fig. 8 is a detail view showing how the 40 strips may be lapped.

Fig. 9 is a detail view of a key used in connection with the arrangement in Fig. 8, and

45 Fig. 10 is a view of a slightly modified form wherein curved sections are employed.

In carrying out my invention, I provide a strip 1 of flexible material, which has a plurality of slots 2 cut in from one edge thereof. The slots 2 are equal in depth to exactly one-half the width of the strip 1. The obvious purpose of this precision is, to obtain the flush fitting of a pair of the strips when pressed upon each other as shown in Fig. 2.

The slots 2 are equally spaced apart and 50 oppositely inclined slots 3 and 4 are cut from the same edge of the strip 1, in the material

between the slots 2. The slots 3 and 4 slope in opposite directions and at angles of 45° with respect to the adjacent edge of the strip 1. The slots 3 and 4 are equal in depth to 60 one-half the width of the strip 1, similarly as are the slots 2. The oppositely sloping slots 3 and 4 do not come exactly to a point where they merge with the adjacent edge of the strip 1, but are so cut into the strip that 65 a short intermediate edge 5 is left.

Slots 6 are cut at equal distances apart in parallel relationship to the edges of the strip 1, substantially as shown in Fig. 1. The slots 6 are shown directly beneath the 70 oppositely sloping slots 3 and 4. The slots 6 may if desired, be cut in other relationship. For instance, if it be so desired, they may be cut beneath the straight slots 2. In either event, the slots 6 correspond in area to the 75 cross sectional area of one of the strips 1, so that a strip may be thrust through the slots 6 as shown at the left of Fig. 4.

The arrangement shown in Fig. 5 although 80 slightly different from that shown in Fig. 1, is substantially the same. Here the strip 1 is made considerably broader and has the arrangement of the slots cut in from each edge. The strip 1 in Fig. 5 is creased or scored at 85 7 so that the edges of the strip may be folded up into the shape of a channel, substantially as shown in Fig. 6. The surface of the strip 1 in Fig. 5 may also be printed as indicated at 8. This printing may represent brick lining, or the outlines of stones set in mortar. 90 The strip 1 in Fig. 5 may also be printed to represent structural steel, so that when the form shown in Fig. 5 is employed in construction, the framework of the building represented may appear as being made of structural steel. 95

The forms of the invention described thus far provide for the edgewise fitting of one strip upon the other. The strips may be laid flat together to obtain other forms of 100 construction. This arrangement is illustrated in Fig. 8. Here it will be seen that a pair of the strips 1 are laid together in such a manner that a pair of the inclined slots 3 coincide. A key 9 shown in Fig. 9 is 105 employed to lock the two strips illustrated in Fig. 8 together. The key 9 has a slot 10 which is twice as wide as the slots in the strip 1 ordinarily are. The purpose of this extra wide slot 10 is, to permit the fitting of 110 the key 9 over the superposed strips 1 in Fig. 8. The slot 10 is fitted upon the solid

portions of the strips 1 at the base of the slots 3 in Fig. 8, and thus locks these two strips together.

A key 11 illustrated in Fig. 7 is used in other connections. For instance, it may be desirable to lock a pair or more of the strips 1 edge to edge, longitudinally. The key 11 is then simply slipped over the open portion of one of the horizontal slots 6 as indicated at 6^x in Figs. 1 and 2, and the corresponding end of another strip is similarly slipped over the other end of the key 11. The two strips are then keyed together firmly enough for all practical purposes.

The keys 11 shown in Fig. 7 are made as they are required, by simply cutting off sections of one of the strips. Such a section is indicated by the dot and dash line 12 in Fig. 1. Another form of key may be made by cutting a portion off at the dot and dash line 13 in Fig. 1. The keys may be cut off in various shapes and sizes to fulfil any particular requirement met in putting up a structure by the use of the strips 1, and the requirement itself will suggest the size and shape of the key. The strips 1 may be manufactured and sold in uniform length if desired. The material of which the strips are made may be sold in rolls and the strips cut therefrom later. The strips are made of any suitable material which is flexible to a certain degree and yet strong enough to withstand considerable rough usage. The material may consist of paste-board, fiber, metal, etc. One advantage of the slotted strips 1 as a toy is, that the strips can be readily fitted together in almost any position very quickly. Each strip includes all the parts that are required to fit a structure together. That is to say, if the keys become lost, more can be made by cutting off sections from one of the strips. The difficulty of keeping a great number of bolts or other fastening devices together, is therefore not experienced.

The form of the invention shown in Fig. 10 is slightly different from the rest, in that the sections 14 are formed in quarter or half curves. If the sections are made in quarter curve, they may be keyed together as at 15 to form half curves as illustrated, by the use of one of the keys 11. In this form of the invention, the various slots are cut on the external periphery of the sections.

The manner of using the toy is thought to be fully understood. When a plurality of the sections are fitted together at right angles with respect to each other as in Fig. 2, the perpendicular slots 2 are employed. As previously stated, these slots 2 extend through one-half the width of the strips 1. The solid portion adjacent the slot 2 of one of the strips, therefore occupies the slot of the other strip, so that the opposite edges of the companion strip lie flush together. This

would not be the case if the slots 2 were less than half the width of the strip in depth.

The strips 1 may be fitted together at angles to each other, as shown in Fig. 3. Here, the purpose of the short intermediate section 5 will be apparent. A number of the strips 1 having been fitted into the inclined slots 3 and 4 as shown in Fig. 3, the outer edges 1^x will be seen to be spaced substantially the same distance apart as the inner edges 1^y are spaced apart. By providing the short intermediate portion 5, the strips 1 fitted together as shown in Fig. 3, will not overlap each other. The structural combinations which may be built up by the use of the differently inclined slots and keys are quite numerous, and will readily suggest themselves to one using the toy.

As indicated by the foregoing, it will be understood that the essence of the invention lies in the peculiar formation of the various slots and the combinations of the slots in the edges of a body of material. Fig. 5 suggests that these slot arrangements may be formed on the periphery of any shaped body as for instance, a relatively broad blank, oval, round, triangular, and other shaped blanks. These variously shaped bodies may then be fastened together according to the particular requirement, by the use of the keys 9 and 11 or portions of these keys.

While the construction and arrangement of the device as illustrated in the accompanying drawing is that of a generally preferred form, obviously modifications and changes may be made without departing from the spirit of the invention or the scope of the claims.

I claim:

1. A structural toy comprising a strip of material having a plurality of perpendicular slots cut in one edge, angularly disposed slots cut in at one edge of the strip, and other slots cut into the strip parallel to the edges thereof.

2. A structural toy comprising a strip having a plurality of sets of slots cut in an edge of the strip, the slots of each set being in similar positions, but adjacent ones of the slots being at angles with each other.

3. A structural toy comprising a strip of flexible material having a plurality of slots cut therein at the edges, certain ones of the slots being disposed at angles with respect to each other and with the edges of the strip.

4. A structural toy comprising a strip of flexible material having a plurality of sets of slots cut therein, the slots of one of the sets being perpendicular to one edge of the strip, the slots of another set being cut at right angles with respect to each other and with respect to said edge of the strip, and the slots of the other set being cut parallel to the edges of the strip.

5. A structural toy comprising a flexible

110

115

120

125

130

strip of severable material having a plurality of sets of slots, the slots of one of the sets being cut in from one edge through one-half the width of the strip and perpendicular to the edge, the slots of the other sets being cut in from the same edge and consisting of pairs, the slots of a pair extending at an angle to each other and cut in from the same edge of the strip to a distance equal to one-half the width of the strip, the slots of the third set being cut into the strip beneath the oppositely extending slots and in parallelism with the edges of the strip.

6. A structural toy comprising a strip of material including a plurality of sets of slots cut into one edge in divergent directions, the outlets of the slots at the edge of the strip being spaced apart to leave an intermediate portion, whereby over-lapping of the edges of other strips when fitting into said diverging slots, is prevented.

7. A structural toy comprising a strip of flexible and severable material including a plurality of sets of slots, one set consisting of slots cut from one edge in diverging directions, the other set consisting of slots cut into the body of the strip parallel to the edges of the strip and in a central position with respect to the diverging slots, portions 30 of said strip providing keys when severed,

on the medial line between the aforesaid sets of slots.

8. A structural toy comprising a strip of bendable material having a plurality of sets of slots cut into the opposite edges, and 35 scored lines on one surface of said strip at the base of each of the sets of slots, to permit bending the edges to form a channel.

9. A structural toy comprising a strip of bendable material having a plurality of sets 40 of slots cut into the opposite edges, and scored lines on one surface of said strip at the base of each of the sets of slots, to permit bending the edges to form a channel, one of the surfaces of said strips being printed. 45

10. A structural toy comprising a strip of material having a plurality of sets of slots cut into one edge, said strip being adapted to be cut at pre-determined places to form keys for entering certain ones of the slots 50 to join other strips together.

11. In a device as described, the combination with a body having a plurality of sets of slots on an edge, adapted to receive other strips in forming a structure, of a key consisting of a portion cut from the body, and adapted to be fitted in any one of said slots, to provide an attachment for another body. 55
